(57) **CLAIM**

The ornamental design for a media player device, as shown and described.

DESCRIPTION

FIG. 1 is a front elevation view of a media player device; FIG. 2 is a rear elevation view thereof;

FIG. 3 is top plan view thereof;

FIG. 4 is an enlarged portion of FIG. 3;

FIG. 5 is a bottom plan view thereof;

FIG. 6 is a first side view thereof;

FIG. 7 is a second side view thereof;

FIG. 8 is a perspective view thereof; and,

FIG. 9 is an enlarged portion of FIG. 8.

The dashed broken lines in the figures illustrate the portions of the design that form no part of the claimed design;

The dot-dot broken lines illustrate unclaimed seams in the design that do not form part of the claimed design.

The dot-dash broken lines frame portions of the figures that show an enlarged view; the broken lines form no part of the claimed design.
